UNITED STATES PATENT OFFICE.

REGINALD A. FESSENDEN, OF WASHINGTON, DISTRICT OF COLUMBIA.

PRODUCING HIGH-FREQUENCY OSCILLATIONS.

932,111.

Specification of Letters Patent. Patented Aug. 24, 1909.

Application filed December 14, 1905. Serial No. 291,739.

To all whom it may concern:

Be it known that I, REGINALD A. FESSENDEN, a citizen of the United States, and resident of Washington, District of Columbia, 5 have invented certain new and useful Improvements in Producing High-Frequency Oscillations, of which the following is a specification.

The invention described herein relates to 10 production of high frequency oscillating currents, the currents so produced being especially adapted for the generation of electromagnetic waves for transmission of energy, particularly in wireless telegraphy 15 and telephony.

The invention is hereinafter more fully described and claimed.

In the accompanying drawings, forming a part of this specification, Figure 1 is a sectional elevation of a condenser having a member movable relative to the other; Fig. 2 is a transverse section of the same; Figs. 3, 4, 5 illustrate modifications in the construction of the condenser, and Fig. 4^a is a 25 section of the structure of Fig. 4 on line 4^a therein. Fig. 6 illustrates a form of sending apparatus embodying my improved condenser, and Fig. 7 illustrates another form of sending apparatus.

It has heretofore been generally assumed 30 as necessary for electromagnetic or wireless transmission of signals, to use a spark-gap for producing oscillations, but I have developed a system for the wireless transmission of energy in which a spark gap is not used and which has been found to be not only more efficient as regards the use of power, but also entirely free from disturbing electrical effects, such as are produced by 35 atmospheric electricity or other stations and is capable of the very highest degree of selectivity.

In the practice of my invention provision 40 is made for causing variations in the amount of current flowing in an oscillating circuit by varying the capacity of the circuit. This can be effected by employing a condenser capable of having its capacity altered very rapidly, thereby producing very sudden 45 changes in the amount of current flowing in the oscillating circuit. Any suitable means 50 may be employed for producing the desired rapid change of capacity, and I have shown in the drawings for illustration several 55 means suitable for that purpose.

In the construction shown in Figs. 1 and 2,

there is a condenser having one of its parts or elements formed by a drum or cylinder, 1, having a series of suitably spaced projections, 2, arranged at an angle to the direction of rotation of the drum, which is mounted on a shaft, 3, driven by a suitable motor, 4. A shell, 5, which may partially, but preferably wholly surround the drum, is provided with a series of inward projections, 6, and is arranged concentric with the drum. Any suitable dielectric may be employed as a solid insulating material or compressed air, or a vacuum may be maintained between the two parts or elements of the 60 condenser. It is preferred, however, to employ a cylinder, 7, of mica, preferably secured inside of the shell, 5. This mica acts as an insulator and permits a higher potential to be maintained between the two parts 65 or elements.

It will be understood by those skilled in the art, that members of the condenser may both be rotated, in opposite directions, thereby doubling the variations or changes 70 of capacity in a given time. In-lieu of making the condenser elements in the form of projections on concentric cylindrical surfaces, the construction shown in Fig. 3, may be employed, consisting of two disks 75 or plates, 8, provided with radial ribs or projections, 9. One or both of these disks are provided with shafts, 10, whereby they may be rotated in opposite directions as by bands 80 10^a, 10^b. While any suitable dielectric 85 may be employed, it is preferred to secure sheets, 11, of mica on the adjacent faces of the disks for the double purpose of avoiding air friction and furnishing a highly efficient 90 insulation.

As shown in Fig. 4, I may use in lieu of one of the disks, 8, a sheet, 29, of mica or glass, rubber or other suitable material, coated with metal, as silver, and the coating or silvering is partially removed so as to form 95 100 radial conducting strips corresponding to the radial ribs or projections, 9, on the disk, 8 (see Fig. 4^a).

It will be understood that two disks or plates of mica, etc., may be employed advantageously, mounted to rotate as in Fig. 3, as on account of their slight weight, they can be rotated at very high speed.

It is evident that when the ribs or projections on the members of the condenser are 110 directly opposite each other, the capacity of the disks with respect to each other, will be

greatest, but will be at a minimum when the ribs on one member are opposite the spaces or depressions between adjacent ribs on the other member. When one of the condenser members is fixed and the other movable, the capacity will vary from maximum to minimum, and from minimum to maximum, as many times per revolution, as there are ribs or projections on the fixed or movable member. If the ribs or projections on the members, for example, are one-tenth of an inch wide and the spaces between adjacent ribs also one-tenth of an inch wide, and the disk moves at a peripheral speed of twenty miles per minute, which I have ascertained is obtainable, the capacity will be changed through a complete cycle, one hundred thousand (100,000) times per second and the electrical oscillations so produced will be of that frequency. If both members be rotated one opposite the other, at the peripheral speed stated, the frequency will be doubled, there being two hundred thousand (200,000) cycles per second.

I have ascertained that, contrary to what has been held by many experimenters, wireless telegraphy can be carried on very efficiently with frequencies as low as twenty thousand (20,000) per second. This corresponds to a peripheral speed when both disks are rotating, of two miles per minute, and hence with my improved method, a very wide range of frequencies can be obtained. By the means described herein, it is possible to obtain more than five hundred thousand (500,000) different frequencies, all of which could act independently and in close proximity.

Any convenient form or arrangement of apparatus can be employed for utilizing the oscillations. As for example, in Fig. 6, is shown a form of apparatus in which the aerial, 12, is grounded and is operatively connected to the secondary, 13, of the transformer, and to the variable condenser, 14. The primary, 15, of the transformer is in the circuit of the source, 16, of voltage (preferably constant) which may have a number of dry or storage cells. A capacity changer, 17, such as hereinbefore described, is also arranged in the circuit of the source of voltage and the primary, 15. A condenser, 26, and an inductance, 27, may also be used if desired, in accordance with methods well known in the art. In operation, when the ribs on one member of the capacity changer, are opposite the spaces between the ribs on the other member, the capacity will be a minimum. When, during the movement of one or both members, the ribs on the two members are opposite each other, the capacity will be maximum and the current will flow into the disks and produce an oscillation in the aerial.

In Fig. 7, is shown another form of appa-

ratus for utilizing the capacity changer. In this arrangement the capacity changer, 17, is connected directly to the aerial, which is grounded. A continuous current generator, as a dynamo, 28, is connected to the aerial and also to ground. By the operation of the capacity changer 17 in this arrangement, the capacity of the aerial to ground is changed every time the ribs on one member pass the ribs on the other member of the changer, and thereby set up an oscillation in the aerial.

The capacity changer may be constructed in many ways, and the ribs may be so shaped and proportioned as to give an approximately sine form in the fluctuations. This is best done empirically, especially if the members are formed of coated insulating material.

In Fig. 4, is shown a form of capacity changer especially adapted to wireless telephony. The mica disk, 29, with its conducting segments, is attached to a resilient diaphragm, 30, by fine platinum rods, 31. On talking into the mouth piece, 32, the disk, 29, is caused to approach and recede from the rotating disk, 8, thereby changing the capacity and the strength of the oscillations in accordance with the sound waves vibrating the diaphragm, 30.

In some cases, it is preferred to arrange one part or member eccentric to the other, as shown in Fig. 5, in which the conducting ribs or portions are arranged to be parallel or approximately so with the ribs or conducting portions on the other disk, when such ribs are moving adjacent to the first disk.

I claim herein as my invention:

1. A capacity changer for electromagnetic electric circuits comprising a condenser and means to rapidly move its effective coöperating members relative to each other, to produce oscillations in the circuit.

2. A high frequency oscillation producer comprising a condenser and means to very rapidly vary the relative distances apart of its effective condensing surfaces.

3. A device for producing oscillations in a circuit comprising a condenser and means to regularly and continuously vary its capacity at a very high frequency, substantially as described.

4. A wireless telegraph sending circuit including as a capacity two conductors separated by a dielectric, and means for very rapidly varying the distance between the effective areas of said capacity conductors whereby to produce oscillations in the circuit by varying the capacity.

5. An apparatus for producing high frequency oscillations in a circuit, comprising two condenser parts or elements movable relative to each other whereby to vary the current and produce oscillations.

6. An apparatus for producing high fre-

quency oscillations in a circuit comprising a condenser and means to move the effective areas of one of its members rapidly with relation to the other, whereby to vary the 5 capacity of the circuit and produce oscillations.

7. In an apparatus for producing high frequency oscillations, a circuit and a capacity changer therein comprising a condenser with 10 its members movable relative to each other, and means for moving said members with sufficiently high frequency to produce electric oscillations.

8. A condenser comprising two members 15 having on their adjacent faces a series of conducting surfaces separated by nonconducting spaces, combined with means for relatively moving the said surfaces very rapidly to produce electric oscillations by alteration 20 of the capacity in a circuit.

9. The combination in a capacity changer of a moving element forming a member of a condenser and having alternate conducting and insulated surfaces, a second member 25 having alternate conducting and insulated portions, means to move one member with

respect to the other, and means actuated by sound waves to move the other member relatively to the first, substantially as described.

10. In wireless telephone apparatus the 30 combination with a condenser and means to rapidly move one of its members with respect to the other, of a sound actuated element attached to and adapted to move one of the elements of the condenser with 35 respect to the other, whereby to produce oscillations in a circuit and at the same time vary the strength of said oscillations in accordance with sound waves substantially as described. 40

11. Means for producing sustained electrical oscillations, of definite frequency, comprising a circuit including a capacity, means for changing the capacity, and means for periodically altering the value of the capacity 45 very rapidly, substantially as described.

In testimony whereof I have hereunto set my hand.
